UNITED STATES PATENT OFFICE

MAURICE P. WHITNEY, OF ELMIRA, NEW YORK, ASSIGNOR TO ECLIPSE MACHINE COMPANY, OF ELMIRA, NEW YORK, A CORPORATION OF NEW YORK

ENGINE STARTER

Application filed July 15, 1927. Serial No. 205,900.

My invention relates to engine starting apparatus for the starting of internal combustion engines more particularly but not necessarily automobile engines, and the object thereof is to provide a simple, efficient and reliable drive or transmission between the prime mover, such as an electric motor and a member of the engine to be started, such as the flywheel thereof. This drive is of the manual shift type, but capable of automatic disengagement of the driving member from the engine member when the engine starts on its own power, and the same is characterized by the provision of an abutment in the path of the backward movement of the driving member or pinion, which is mounted upon a screw shaft or sleeve with long lead threads whereby after this disengagement of the pinion from the engine member with the screw sleeve in still advanced position, such pinion will be brought to its normal position on such sleeve when the operator relieves his pressure upon the manually operated shifting connections.

In the drawings, Figure 1 is a sectional elevation of a starting apparatus embodying my invention and illustrating the parts in their normal position;

Fig. 2 a similar view but showing the parts in operated or cranking position; and

Fig. 3 a section on the line 3—3 of Fig. 2. The embodiment of my invention as herein shown is selected for the purpose of a clear and definite description of my invention which may partake of different constructions and forms.

As herein shown, the prime mover is an electric motor 1 and as in the present instance, the drive is of the direct type, the rotatable driving shaft 2 is the extended armature shaft of the motor. The drive proper is mounted upon and driven by this shaft, the same being bodily shiftable by manual means to bring the driving member into engagement with the engine member and being restored to normal position as to the entire assembly by such manual means and also automatically as to the driving member or pinion when the engine starts on its own power and in case the operator should not

release the pressure upon the manual means.

As herein shown, the drive comprises a hollow shaft or sleeve 3 which is mounted upon the shaft 2 for longitudinal movement thereof and rotary movement therewith for which purpose this sleeve is splined to the shaft by means of the splines 4. This sleeve is provided with long lead screw threads 5 toward its outer end, and at this end, there is provided a stop means such as a stop nut 6.

The driving member is here in the form of a pinion 7 threaded upon the screw sleeve and provided with a weighted disk 8 at one end thereof. The inner end of the sleeve is provided with parallel flanges 9 to cooperate with the manual shifting means hereinafter described. The shaft 2 is supported at its outer end in a bearing 10 formed in a bracket or support 11.

A countershaft 12 parallel with the driving shaft 2 is mounted at one end in a support 13 in the bracket 11 and at its other end in a support 14 in the electric motor frame. This countershaft supports an abutment which is extraneous of the drive proper and cooperates with the pinion 7 and which is in the form of a yoke 15 having a sleeve 16 adjustably mounted upon the countershaft 12 intermediate its length and having at its lower end arms 17 which straddle the screw sleeve and have a spread greater than the diameter of the disk portion of the pinion. These arms 17 are provided at their lower ends with rollers 18 projecting inwardly from the inner faces of these arms 17 and into the path of movement of the disk 8 of such pinion.

Referring to the manually operated means, the same consists of a shifter arm 19 cooperating with the flanges 9, with some lost motion therewith, and having at its upper end a sleeve 20 which is mounted to slide upon the countershaft and to be advanced to the left (Fig. 1) against the tension of a coil spring 21 interposed between the stationary sleeve 16 and the movable sleeve 20. Suitable operating connections or linkage are provided for operation by the operator or driver for actuating the drive and also actuating the switch for controlling the current to the motor. In the present instance, such operat-

ing connections comprise a foot operated plunger 22 mounted to slide through the usual foot boards 23 of an automobile and a link 24 pivotally connected to the inner or lower end of the plunger 22 and the sleeve 20. This plunger 22 carries in an arm or bracket 24 an adjustable contact screw 26 in whose path of movement is arranged a button 27 of an electric switch 28 which is electrically connected with the electric motor by connections (not shown).

Describing a cycle of operation of the apparatus and beginning with the parts in their normal position shown in Fig. 1, when it is desired to crank and start the engine, the operator depresses the plunger 22 whereupon the movable sleeve 20 after a slight movement to the left will shift the screw sleeve 3 to the left together with the pinion 7 which movement is against the tension of the spring 21. The parts now assume the position shown in Fig. 2 at which time the switch button 27 has already been actuated, the particular time thereof being capable of regulation by means of the screw 26, so that the particular time of closing the switch with relation to the position of the pinion in its engagement with the engine member may be predetermined.

The parts are now in cranking position, and when the engine starts on its own power, the pinion will be practically instantly screwed backwardly upon the screw sleeve and out of mesh with the teeth 29 of the flywheel 30 even faster than the operator can act in releasing his pressure on the pedal or plunger 22. At the time, the pinion is against the abruptly formed end or heel 31 of the screw threads of the sleeve, but does not contact the rollers 18 of the yoke. In this position, the engine flywheel is rotating without any connection with the starting motor and such motor is still rotating due to the closure of the switch, but under no load. As soon as the operator releases the pressure on the shifting mechanism, the electrical contact is broken which cuts off current from the starting motor and then the screw sleeve is drawn back to normal disengaged position by means of the spring 21 as above described. As the sleeve is thus forced back towards its disengaged position, it is drawn through the pinion which by virtue of the long lead threads of the sleeve rotates against the rollers until the parts assume the normal position shown in Fig. 1 ready for the next start.

In the event that the operator should fail or delay to release his pressure on the plunger 22, the pinion 7 will nevertheless demesh, doing so automatically as above explained whereupon the pinion will take the position shown in dotted lines in Fig. 2.

In the normal position shown in Fig. 1, the pinion is against the stop nut of the sleeve and is prevented from any substantial drifting back on such sleeve by means

of the rollers 18 of the abutment or yoke described. In this position, the rollers do not usually touch the pinion disk, as a slight clearance is provided as shown in this drawing.

I claim:

1. An engine starter drive including a rotatable driving shaft, a sleeve shiftable longitudinally thereon and rotated thereby, a driving member mounted on the sleeve for longitudinal movement thereon and rotary movement therewith adapted when advanced longitudinally to engage a member of the engine to be started, an abutment arranged in the path of the backward longitudinal movement of the driving member and made in the form of a yoke extending on either side of the driving member and having projections engaged by said driving member, and manually operable means for shifting the sleeve longitudinally.

2. An engine starter drive including a rotatable driving shaft, a sleeve shiftable longitudinally thereon and rotated thereby, a driving member mounted on the sleeve for longitudinal movement thereon and rotary movement therewith adapted when advanced longitudinally to engage a member of the engine to be started, an abutment arranged in the path of the backward longitudinal movement of the driving member and made in the form of a yoke extending on either side of the driving member, rollers in the arms of said yoke adapted to be contacted by the driving member and to act as a back stop therefor, and manually operable means for shifting the sleeve longitudinally.

3. An engine starter drive including a rotatable driving shaft, a sleeve shiftable longitudinally thereon and rotated thereby, a driving member mounted on the sleeve for longitudinal movement thereon and rotary movement therewith adapted when advanced longitudinally to engage a member of the engine to be started, an abutment arranged in the path of the backward longitudinal movement of the driving member, a countershaft by which such abutment is supported, and a manually operable shifting device mounted to slide upon the countershaft and operably connected with said sleeve.

4. An engine starter drive including a rotatable driving shaft, a sleeve shiftable longitudinally thereon and rotated thereby, a driving member mounted on the sleeve for longitudinal movement thereon and rotary movement therewith adapted when advanced longitudinally to engage a member of the engine to be started, an abutment arranged in the path of the backward longitudinal movement of the driving member, a countershaft by which such abutment is supported, a manually operable shifting sleeve mounted to slide upon the countershaft and operably connected with the first named sleeve, and a

spring disposed between the shifting sleeve and the abutment.

5. An engine starter drive including a rotatable driving shaft, a sleeve shiftable longitudinally thereon and rotated thereby and having long lead screw threads, a driving member threaded on said threads, an abutment, rollers carried by such abutment and arranged in the path of backward longitudinal movement of the driving member, said threads ending abruptly at one end to form positive stops for the backward movement of the driving member and preventing contact of the driving member with the rollers when the driving member is disengaged while the sleeve is still in its shifted position.

10 6. An engine starter drive including a rotatable driving shaft, a sleeve splined thereon and having at one end a stop means and adjacent long lead threads, a pinion threaded on said threads and having a disk at one end, an abutment in the form of a yoke straddling the sleeve and pinion, a pair of rollers mounted in the arms of such yoke and arranged in 15 the path of backward longitudinal movement of said disk, and manually operable means for shifting the sleeve longitudinally.

20 7. An engine starter drive including a rotatable driving shaft, a sleeve shiftable longitudinally thereon and rotated thereby and having screw threads thereon, a driving member threaded on said threads, a slid able shifting device for said sleeve, a member on which it slides, and an abutment mounted on 25 said member and arranged in the path of backward longitudinal movement of the driving member.

In testimony whereof, I have subscribed my name.

MAURICE P. WHITNEY.
